Primary Examiner — Austin Murphy(74) *Attorney, Agent, or Firm* — Zagorin Cave LLP; Robert W. Holland(57) **CLAIM**

We claim the ornamental design for a server rack handle, as shown and described.

DESCRIPTION

FIG. 1 is a front perspective view of the server rack handle comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a front perspective environmental view thereof. Broken lines shown in the drawings illustrate portions of the server rack handle, and form no part of the claimed design.
